(57) **CLAIM**

The ornamental design for a wine cradle as shown and described.

DESCRIPTION

FIG. 1 is a perspective view of a wine cradle taken from the top, right, and front;

FIG. 2 is another perspective view of the wine cradle taken from the top, left, and back;

FIG. 3 is a front elevation view of the wine cradle of FIG. 1;

FIG. 4 is a back elevation view of the wine cradle of FIG. 1;

FIG. 5 is a right elevation view of the wine cradle of FIG. 1;

FIG. 6 is a left elevation view of the wine cradle of FIG. 1; FIG. 7 is a top plan view of the wine cradle of FIG. 1; and, FIG. 8 is a bottom plan view of the wine cradle of FIG. 1. The broken lines shown in the drawings illustrate portions of the wine cradle that form no part of the claimed design. The stippling shown in FIGS. 1-8 depicts surface shading.

1 Claim, 7 Drawing Sheets
